COMBINED CHAIR AND TABLE

Samuel R. Mickelson, New Bedford, Mass.

Application December 9, 1955, Serial No. 39,259

Term of patent 14 years

(Cl. D15—1)

Figure 1 is a side elevational view of the combined chair and table embodying my new design, illustrated in position for use as a chair;

Figure 3 is a side elevational view of the combined chair and table illustrated in position for use as a table, and

I claim:

The ornamental design for a combined chair and table, as shown.
